Attns*

UNITED STATES PATENT OFFICE.

GEORGE J. CAPEWELL, OF CHESHIRE, CONNECTICUT.

CLOTHES-DRIER.

SPECIFICATION forming part of Letters Patent No. 360,275, dated March 29, 1887.

Application filed May 14, 1885. Serial No. 165,519. (No model.)

To all whom it may concern:

Be it known that I, GEORGE J. CAPEWELL, of Cheshire, in the county of New Haven and State of Connecticut, have invented certain new and useful Improvements in Clothes-Driers, of which the following is a description, reference being had to the accompanying drawings, where—

Figure 1 is a view of my improved device with the parts extended and with parts cut away to show construction. Fig. 2 is a view in horizontal section of the device on plane denoted by line x x of Fig. 1, showing the radial arms in plan view.

15 The object of my invention is to provide an improved device for supporting clothes while drying, which device is adapted to be secured to the ceiling of a room, and has means for closing or folding it up out of the way when not in use and for readily extending it so as to be accessible when wanted.

It consists in the combination of bracket, support, and arms for holding the clothes with means for operating the device, as more particularly hereinafter described, and particularly pointed out in the claim.

In the accompanying drawings, the letter a denotes a bracket, preferably of cast metal, with a screw, b , projecting from the upper side of the bracket, which also supports the pulley c , and projecting downward from the bracket an extensible standard, d . In the form shown this standard is made up of a stem, d' , on which slides a tube, d'' , which is prevented 35 from sliding off the bottom of the stem by means of a pin, collar, or like stop device, e . On the outside of this tube d'' is arranged a hub, f , bearing in sockets in a disk-like extension of the hub a plural number of radially-extending arms, g . The hub is preferably of metal cast to shape with the sockets formed in the casting, and the arms, which are readily inserted in such sockets, are preferably of wood.

As a means for raising and lowering the

hub and connected arms, I use in this form of 45 my device a cord, h , which is fast to the hub on one side, and, after passing through the pulley c , is let down through a hole in the hub and between the jaws of a clamp device, that is preferably fast to the lower end of the tube d'' . This clamp device consists of a cam-lever, i , so pivoted in its support as to be adapted to clamp the cord between the roughened grasping-face of the cam and the side of the tube. This or any other well-known form of 55 clamp device may be used for this purpose.

This improved drier is secured to the ceiling of a room by means of the screw b , and the extensible support projects downward, not far enough, however, to be in the way of persons 60 moving about in the room when the device is closed. When desired for use, the cord is released from the clamp, the hub, with its clothes-supporting arms, lowered far enough to be within easy reach, and when clothes have been 65 hung upon the arms the whole may be lifted out of the way by means of the cord and the clothes left to dry.

The hub is capable of a rotary motion about the standard; or a swivel may be introduced 70 within the bracket; but it is desirable that the standard should be rigid or fastened against side-play.

I claim as my invention—

The herein-described improved clothes-drier, consisting of the combination of the bracket bearing a pulley, means for securing said bracket to the ceiling, the extensible standard, comprising the rigid stem and the tube sliding thereon, a cord-securing device on 75 said sliding tube, and a cord secured to the hub, passing over the pulley and extending to the before-mentioned cord-securing device, substantially as shown and described.

GEORGE J. CAPEWELL.
